UNITED STATES PATENT OFFICE.

CHARL P. LARSEN, OF PAUL'S VALLEY, INDIAN TERRITORY.

DESIGN FOR A HARNESS-HOOK.

SPECIFICATION forming part of Design No. 32,038, dated December 26, 1899.

Application filed November 29, 1899. Serial No. 738,739. Term of patent 7 years.

To all whom it may concern:

Be it known that I, CHARL P. LARSEN, a citizen of the United States, residing at Paul's Valley, in the county of Chickasaw, Indian Territory, have invented and produced a new and original Design for Harness-Hooks; and I do hereby declare the following to be a full, clear, and exact description of the same, reference being had to the accompanying drawings, forming a part thereof.

Figure 1 is a plan view of a harness-hook, showing my new design. Fig. 2 is a perspective view of the same, and Fig. 3 is a side view of the hook.

My new and original design consists of an oval loop having a straight shank extending outward from one side of said loop and a spiral hook projecting laterally from the end of the shank, all formed from a single integral piece of metal. The spiral hook as it merges from the shank curves upward upon the upper side of said shank, and thence extends laterally from one side of the shank to form spiral coils of comparatively quick pitch. This hook portion comprises about two convolutions or coils, and the metal forming the outer coil is gradually tapered until it reaches the pointed terminal end.

The metal from which the hook is formed is cylindrical in cross-section and is made from a single rod or length of material, having a gradually-tapered portion at one end thereof, from which the terminal end of the hook is formed.

As shown in Fig. 3, when viewed from one side the hook portion of my design presents a circle or ring the inner diameter of which is slightly greater than the sectional diameter of the metal from which the loop and shank are formed.

The essential feature of my design is the spirally-formed hook extending from the top and to one side of the shank and the outer coil of the spiral being gradually tapered to a terminal point.

Having thus fully described my invention, what I claim as new, and desire to secure by Letters Patent, is—

The design for a harness-hook, as herein shown and described.

In testimony whereof I affix my signature in presence of two witnesses.

CHARL P. LARSEN.
